UNITED STATES PATENT OFFICE.

HALVER R. STRAIGHT, OF ADEL, IOWA.

METHOD OF TREATING OIL-BEARING SHALE.

Application filed July 31, 1918. Serial No. 247,694.

To all whom it may concern:

Be it known that I, HALVER RUFUS STRAIGHT, a citizen of the United States, and a resident of Adel, in the county of 5 Dallas and State of Iowa, have invented a certain new and useful Method of Treating Oil-Bearing Shale, of which the following is a specification.

The objects of my invention are to provide an improved method of treating oil-bearing shale, whereby the more volatile and essential ingredients thereof may be quickly and easily removed so that large quantities of the oil-bearing shale may be thus treated 15 in a comparatively small time.

A further object is to provide a method of this kind, in which the shale is successively subjected to increasing degrees of temperature, whereby the more volatile vapors are 20 first removed and the heavier vapors later removed, and whereby when the vapors are thus removed from the shale they are kept separate and not again commingled, to thereby economize in the final treatment, cleaning 25 and purification of the ingredients.

Still a further object is to provide an improved method of treating oil-bearing shale, whereby the more volatile ingredients, such, for instance, as gasoline, kerosene and light 30 lubricating oils, may first be removed without subjecting them to such temperatures as would tend to injure the cast metal containers for the shale, so that if desired the less volatile ingredients, such, for instance, as 35 heavy fuel oils, paraffin and nitrogen, may be separately subjected to such high degrees of temperatures as may be necessary to vaporize them, in a separate fire-brick container for the shale.

40 Still a further object is to provide an improved method of preventing the incoming supply of fresh shale from injuring the cast iron shale containers in the vaporizing chamber by reason of subjecting them to excessively low degrees of temperature on account of the said incoming supply of shale.

Still a further object is to provide an improved method of treating the supply of shale within the vaporizing chamber, where- 50 by all of the shale is rapidly subjected to high temperatures and is prevented from fluxing, and whereby the vapor is readily removed from the mass of heated shale.

55 Still a further object is to provide an im- proved method of removing the less volatile vapors and gases from the shale, by first sub-

jecting them to relatively high temperatures, and then confining them in a suitable container and supplying oxygen or air to the heated mass for utilizing the remaining combustible ingredients of the shale for the purpose of supplying additional heat to liberate the less volatile ingredients. 60

My invention consists in the arrangement and combination of the various steps of the 65 process, whereby the objects contemplated are attained, as hereinafter more fully set forth and pointed out in my claims.

For the purpose of assisting in an understanding of my improved method, I have 70 shown in the accompanying illustration, an apparatus by which the method may be carried out, and I shall first briefly describe the apparatus.

The reference numeral 10 indicates a sub- 75 stantially horizontally arranged heating chamber, in which the heat is supplied by gas or in any suitable way. Above it is a horizontally arranged vapor chamber 11.

The heating chamber and the vapor chamber 80 are separated by a shale-carrying conveyer 12, the shale containers of which may be made of cast iron, and are made to fit tight enough together to form a substantially flame-tight partition between the combustion chamber and the vapor chamber. This conveyer is continually advanced at a slow rate of speed during the operation of the apparatus. 85

At one end is a hopper 13, through which 90 the shale is fed continuously to the conveyer. At intervals throughout the length of the vapor chamber are the transverse partitions 14 and 15, to separate the vapor chamber into compartments. Communicating with 95 each compartment is a vapor pipe 16 leading to a condensation coil 17 which discharges into a suitable container 18. In the event that any fixed gases are discharged into the containers 18, I have provided a pipe 19, 100 communicating with each container and running to a point of discharge, for the purpose of carrying off such fixed gases.

To assist in the liberation of vapors from the body of shale on the conveyer, I have 105 provided a steam pipe 20 having downwardly and then forwardly extended branches to project under the layer of shale on the conveyer and to discharge steam into the layer of shale near the bottom of the 110 layer.

To further assist in the liberation of the

vapors and present new parts of the mass to the hotter part of the conveyer, I have provided a series of stirring devices 21 fixed in position within the vapor chamber and having their stirring blades projecting downwardly close to the bottom of the layer of shale.

For the purpose of preheating the shale to raise its temperature so that it will not chill 10 the cast iron conveyer members, I have provided a fan 22 communicating at one end with the combustion chamber and discharging at its other end into the interior of the hopper 13. It is controlled by a damper 23, 15 so that the desired amount of heat may be furnished at all times.

As will be hereinafter explained, the more volatile ingredients are removed from the shale in the part of the apparatus just described, but it is not desirable to subject the cast iron container to sufficiently high temperatures to remove all of the valuable ingredients, as it would tend to retard the treatment of the shale and reduce the capacity 25 of the apparatus.

In cases where the quality of the shale and the selling price of the less volatile ingredients make it desirable to do so, I have provided a separate apparatus in which the 30 temperatures may be sufficiently, conveniently and economically raised to such a degree as to remove such ingredients, for instance, as heavy fuel oils, paraffin and nitrogen.

35 This apparatus comprises a rotary cylindrical body portion 24, preferably provided with fire-clay lining. This body portion is supported in an inclined position upon the rollers 25 and 26, and is rotated by means of 40 the roller 27 driven by the pulley 28.

At the upper end of the cylindrical container is a receiving spout 29, into which the contents of the conveyer 12 are discharged in their heated condition. Within the central portion of this rotary shale container is a cone-shaped heating device 30, projecting a considerable distance into the container from the bottom thereof, and which is perforated, and into which the combined gas, 45 air and steam nozzle 31 is projected. This nozzle communicates with a steam supply pipe 32 and a gas supply pipe 33, and a valve 34 is provided, by means of which air may also be introduced.

50 The bottom of the cylindrical chamber 24 is perforated so that the spent shale may be discharged therefrom through the discharge pipe 35.

The valuable vapors and gases arising 60 from the heated material are carried away through a vapor pipe 36 which extends through the openings at the upper end of the cylindrical chamber 24.

In carrying out my improved method by 65 the use of the apparatus just described, I

supply heat to the combustion chamber 10 until the desired amount is reached, and I then continuously advance the conveyer, and as the conveyer is advanced each compartment thereof is filled with shale from the 70 hopper, which delivers it to the conveyer in a thin, wide layer of uniform thickness. The shale is preferably reduced to small particles before being placed in the hopper.

In order that the shale may not be so 75 cold, when it enters the conveyer, as to injure the material of which the conveyer is formed, I preferably pre-heat the shale by forcing heat into it from the combustion chamber, so that it is raised to a temperature of two or three hundred degrees Fahrenheit before being delivered to the conveyer.

As the shale passes through the first compartment of the vaporizing chamber, its 85 temperature will be greatly raised until the more volatile vapors are liberated therefrom, and these more volatile vapors are all liberated from the shale before it passes under the first partition 14.

In order to assist in the vaporization, I inject steam into the mass of moving shale, and also agitate it, so that the vapors, as soon as liberated, can easily and rapidly pass through the thin layer of shale on the 95 conveyer. In this first compartment of the vapor chamber, one of the more volatile vapors which is liberated is gasoline.

By my improved method the gasoline and the other more volatile vapors that are liberated in the first compartment of the vapor chamber, are kept separated and condensed in a separate chamber, and are never thereafter commingled with the other ingredients. The gasoline thus liberated and separated 105 from the less volatile ingredients, may be readily and easily and inexpensively purified and separated from the other highly volatile ingredients that were liberated with it.

When the thin layer of shale has passed the first partition 14, it becomes heated to a higher degree, and while passing through the second compartment of the vapor chamber it is again subjected to the action of 115 steam, and is stirred, and hence other ingredients that require higher temperatures are liberated in the form of vapor, such, for instance, as kerosene.

The vapors thus liberated in the second 120 compartment are removed and condensed and placed in a separate container, and may be purified and separated from the other ingredients easily and inexpensively.

In the last compartment of the vapor 125 chamber the shale is subjected to still greater temperatures, and also treated with steam, and stirred, so that other ingredients which require higher temperatures for their vaporization, are thereby liberated, and re- 130

moved, condensed and placed in a separate compartment, such, for instance, as the lighter lubricating oils.

In order to remove such ingredients from oil-bearing shale, for instance, as the heavier fuel oils, paraffin and ammonia sulphate, it is necessary to subject the shale to such high temperatures as would injure the cast iron conveyer. Hence by my improved method 10 the more volatile ingredients may be removed before it is necessary to employ such high temperatures as would injure cast iron and make it impractical to treat the shale in an apparatus of the kind illustrated and described.

After removing the more volatile ingredients, such, for instance, as the ones mentioned, there remain other valuable ingredients in the shale, which, however, must be subjected to relatively high temperatures before they are separated. Furthermore, when the shale has been subjected to such temperatures as will liberate the heavier oils, the mass of shale has been heated to such 25 an extent that it of itself becomes combustible when mixed with a sufficient quantity of air. For the purpose of utilizing this heated mass of shale for further raising its temperature to liberate the less volatile ingredients, I have provided for discharging the heated mass of shale into a separate compartment and supplying air to it in sufficient quantities to permit the combustible of the shale to be partly consumed. By 30 regulating the amount of air, the temperature can be regulated with great accuracy. It is to be understood in this connection that only sufficient air is admitted to partly consume the combustible of the heated shale and to raise the temperature to just the 35 amount required for liberating the less volatile ingredients, such, for instance, as heavy fuel oils, paraffin and nitrogen.

In the event that additional heat is required, such, for instance, as when starting the apparatus, a gas flame is introduced into the center of the mass of heated shale, and this gas can readily and inexpensively be obtained by piping it from the various containers into which the more volatile ingredients have been discharged, for the reason that during the distillation of the more volatile ingredients there are certain fixed gases which are also liberated and discharged into said containers, and these fixed gases may be thus economically utilized. They are also utilized to as great an extent as may be possible, in supplying heat to the combustion chamber of the first part of the 50 apparatus.

I also provide for injecting steam into the mass of heated shale in the rotary container, for the purpose of assisting in the liberation of the vapor.

65 The vapors which contain the gasoline,

kerosene and the lighter lubricating oils are all liberated from the shale before the vapors which contain sulphur. It is difficult and expensive to remove sulphur from gasoline, kerosene, light lubricating oils and the like. In the methods employed heretofore, where all of the vapors are commingled after they have been liberated from the shale, it is necessary to perform the difficult and expensive operation of later removing certain 70 ingredients, such, for instance, as sulphur, from the oil.

By means of my improved process, however the sulphur and similar ingredients are never commingled with the lighter vapors, 80 and hence no later act of separation or purification need be performed, thus effecting a material economy in the operation of the device.

By the use of the term "shale" in this application I refer to any material containing volatile hydro-carbon of any nature.

I believe my method of treating oil bearing shale may be put to a great variety of uses, and might, for instance, be used in 90 treating coal where coke is one of the by-products.

I claim as my invention:

1. The method of treating oil bearing shale which consists in first heating the shale 95 to such temperatures as will remove the more volatile ingredients, then depositing them in a closed container, and then supplying oxygen in measured quantities to the interior and central portion of the mass of heated 100 shale, then agitating the material about the point which the oxygen is supplied by rotating the same, for utilizing the combustible properties of the shale to further raise the temperatures to a high degree, and to 105 prevent the mass of material from fusing together while the less volatile ingredients are being liberated.

2. The method of treating oil bearing shale which consists in first heating the shale 110 to such temperatures as will remove the more volatile ingredients, then depositing them in a closed container, and then supplying oxygen and combustible fuels in measured quantities to the interior and central 115 portion of the mass of heated shale, then agitating the material about the point which the oxygen is supplied by rotating the same, for utilizing the combustible properties of the shale to further raise the temperatures 120 to a high degree, and to prevent the mass of material from fusing together while the less volatile ingredients are being liberated.

3. The method of treating oil bearing shales which consists in continuously depositing the shale in a closed container, then supplying combustible fuels and oxygen in measured quantities to the exterior and central portion of the mass of shale within the container for heating the shale and utilizing 125

the combustible properties of the same, and further raising the temperatures to liberate the less volatile ingredients, and agitating the material about the point in which the 5 fuel is injected by rotating the mass of shale about the said point of fuel injection as a center.

4. The method of treating oil bearing shale which consists in continuously depositing the shale in a closed container, then 10 supplying combustible fuels and oxygen in measured quantities to the exterior and central portion of the mass of shale within the container for heating the shale and utilizing

the combustible properties of the same, and 15 further raising the temperatures to liberate the less volatile ingredients, and agitating the material about the point in which the fuel is injected by rotating the mass of shale about the said point of fuel injection as a 20 center, the said rotation being in such a manner that the portion of the shale from which the oil has been extracted will move to a point below the point from which the fuel is injected and continuously withdrawn 25 from the container at said point.

Des Moines, Iowa, July 13, 1918.
